CAKE AND SKEIN TREATING SYSTEM

Adolf Rüsch, Sydowsaue, near Stettin, Germany,
assignor to American Glanzstoff Corporation,
New York, N. Y., a corporation of Delaware

Application October 6, 1931, Serial No. 567,317
In Germany November 20, 1930

10 Claims. (Cl. 18—8)

This invention relates to a novel washing machine arrangement to be used in the washing and treating of spinning cakes, produced, in the artificial silk industry, by the centrifuge spinning process.

In the production of artificial silk by this process, the threads or filaments, having been extruded into a suitable spinning medium, are led over a guide into a rotating pot. The bodies 10 of thread thus produced are known as cakes. The cakes are then subjected to several chemical treatments such as desulphurizing, copper removal, bleaching, deacidifying, and sizing. These 15 treatments are included in the so-called "wet treatment" steps, and may be performed by drip washing, sprinkling or dipping.

It is an object of this invention to provide a washing and/or treating unit with means which will conduct the cakes of yarn through the unit 20 in such a manner that the various treatments necessary, may be effectively carried out.

It is another object of this invention to provide suitable means whereby the yarn may be changed from the round cake form to skein form.

25 It is a further object of this invention to provide means whereby the yarn skeins may have their position reversed on the carrier rods thus affording a suitable method by which all of the threads of each skein or cake may be thoroughly 30 subjected to the various treating liquids.

A still further object of this invention is to provide means whereby the carrier rods may be easily secured to the endless transporting belt or chain.

35 These and other objects of this invention will become more apparent from a perusal of the following description and a study of the drawings in which:

40 Figure 1 is a diagrammatic view of the treating arrangement;

Figure 2 is a detailed fragmentary view of the unit showing the manner in which the skeins or cakes are mounted on the carrier rods;

45 Figure 3 is a view showing one method of securing the skein carrier rods to the endless conveyor chain or belt;

Figure 4 is a view of another method of securing the skein carrier rods to the endless conveyor 50 chain or belt;

Figure 5 is a detailed view of the endless conveyor chain or belt and showing the mechanism used to reverse the position of the skeins on the carrier rods; and

55 Figure 6 is a detailed view showing a second

method and mechanism of reversing the position of the skeins on the carrier rods.

Referring now more particularly to the drawings, there is shown a skein treating unit through which the skeins 1, carried by the carrier rods 60 or sticks 2, are transported in a zig-zag manner by means of a pair of endless conveyor chains or belts 3. Each chain comprises a plurality of links secured together by means of bolts, 5.

Mounted at spaced intervals on the endless 65 conveyor chains or belts are means whereby the skein carrier rods may be secured or attached thereto. In Figure 3 there is shown one method of attaching these rods to the chains, and comprises a tube 4 having an opening 21, formed 70 therein of such a size as to snugly receive the shank of the bolt. The tubes are sufficiently wide and deep so that the ends of the carrier rods can be very easily inserted therein. In Figure 4 the bolt itself is provided with an opening 75 5' in which the end of the carrier rod fits.

The endless conveyor chains or belts are driven by the sprockets 6 and 7 arranged in pairs. The corresponding sprockets are secured to the same drive shaft which passes through the machine in 80 a longitudinal direction. All of the connecting drive shafts of the individual sprocket pairs may be driven by any suitable source of power, or only the shafts in the upper part of the unit need be driven.

Between two corresponding upper located sprockets there is installed the cake or skein turning or reversing cylinders 8, as is clearly shown in Figure 5, which are secured in any desired manner to the respective connecting drive shaft. 90 The purpose of these cylinders is to turn the skein or cakes 180° on the carrier rods. The operation of these cylinders is as follows: The skein 1' supported at 2' by a carrier rod is prevented from swinging freely on the carrier rods by the cylinder 8. With the continuous movement of the conveyor chain the skein will reach the position indicated by 1'' where the carrier rod will not be supporting the skein which is held wholly by engagement with the cylinder. When the skein has passed over the cylinder that part of the skein which was against the carrier rod before its passage over the cylinder will now be swinging free as indicated at 1'''. In the right hand part of the Figure 5 the skeins are not 105 turned but are allowed to swing free during their passage over the chain wheel as indicated at 1''''.

In Figure 6 there is shown a modified form of mechanism for use in reversing the position of the skeins on the carrier rods. This mecha- 110

nism comprises two parallel boards 10 and 11 secured to correspondingly shaped members 10' and 11' of a cylindrical member secured to a shaft 9. These boards are positioned tangentially to the said shaft. During the gradual movement of the chain wheels 6' the rising cakes or skeins are caught flat by one of the boards 10, lifted up and then dropped onto the carrier rod after they have been turned through an angle of 180°.

10 Before the spinning cakes supported by the carrier rods are inserted into the washing or treating machines, they are in a more or less round form 1a, which gradually changes into a skein-like form due to the treating liquids spraying thereagainst or by contact therewith. It has been found that reliance cannot be placed on such methods of changing the shape of the cake, and, therefore, mechanism has been provided 20 which will mechanically change the cakes into a uniform skein like shape prior to the wet treatment and particularly before they have been subjected to the turning arrangement.

This mechanism as clearly shown by Figures 1, 25 2 and 5 comprises a pair of rods 12 and 13 located on either side of the conveyor chains or belts. Positioned above this pair is a second pair 14 and 15. The cakes 1a, supported on the carrier rods, and still having their round form, pass 30 first upon the movement of the conveyor chain or belt between the first pair of rods 12 and 13 by means of which they are partially compressed into skein form as shown at 1b. Further movement of the conveyor chain or belt moves the partially compressed cakes through the upper pair 35 of rods which imparts to them the final skein form 1c. It is obvious, however, that this compression of the cakes into skein form may be accomplished by using only one pair of rods, but 40 the use of two pairs of rods, located as described, prevents or aids in the prevention of any injury to the threads making up the cake.

At the places where the skeins are placed in and removed from the machine there are installed vertically disposed partitions 16 and 17, made of glass or other suitable material, which prevents the workers from being splashed with the treating liquid.

The treating liquids are brought into contact 50 with the skeins by means of suitable spraying nozzles 18 and 19 located at convenient points in the system. Containers 20 are positioned below the skeins to collect the used treating liquids. The spraying nozzles can be so arranged on the extension over the cakes that the treating liquids may fall from one series of cakes to another, or the spinning cakes can be dipped in troughs containing treating liquids placed below the turning points of the endless conveyor.

60 If one and the same chain-batch is to be passed through all the respective treating baths in sequence, care has to be taken that the materials of which the parts of the device are made are equally resistant to the attacks of the different baths.

It will be readily appreciated that by the above description, arrangement is provided for a simple and efficient means for handling the skeins while subjecting them to the desired wet treatment.

70 While the present invention is more particularly adapted to handle cakes formed by the "pot-spinning" process during the wet treatment thereof, it is not limited to such use but may be employed for handling skeins of yarn during the wet treatment thereof which may be produced

by methods other than the pot-spinning process.

While there has been disclosed in this specification one or more forms in which the invention may be embodied it is to be understood that they are shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for what it is desired to secure Letters Patent, is:

1. In a device of the class described, a pair of endless conveyor chains mounted for movement in a treating unit for skeins, aligned holding means carried by said chains, carrier rods positioned in said holding means, and means to reverse the position of the skeins on said carrier rods located at intervals throughout the unit.

2. In a device of the class described, a pair of endless conveyor chains mounted for movement in a treating unit for skeins, aligned holding means carried by said chains, carrier rods positioned in said holding means, means to reverse the position of the skeins located at intervals throughout the unit, said means comprising cylindrical members adapted to engage the skeins.

3. In a device of the class described a treating unit, a pair of endless conveyor chains for skeins, sprockets engaging the said chains, and so located as to lead the chains in a zig-zag path throughout the unit, shafts for rotating said sprockets, and means secured to certain of said shafts for reversing the position of the skeins.

4. In a device of the class described a treating unit, a pair of endless conveyor chains for skeins, sprockets engaging the said chains, and so located as to lead the chains in a zig-zag path throughout the unit, shafts for rotating said sprockets, carrier rods removably secured to said conveyor chains, means secured to certain of said shafts for reversing the position of the skeins on said carrier rods.

5. In a device of the class described a treating unit, a pair of endless conveyor chains for skeins, sprockets engaging the said chains, and so located as to lead the chains in a zig-zag path throughout the unit, shafts for rotating said sprockets, means secured to certain of said shafts for reversing the position of the skeins comprising cylindrical members located on certain of said shafts adapted to engage and hold the skeins passing thereby.

6. In combination, a treating unit, upper and lower drive shafts, pairs of sprockets secured thereto, a pair of endless conveyor chains driven by said sprockets and adapted to carry skeins, and means located on the upper drive shaft between a pair of sprockets adapted to reverse the position of the skeins as they pass the said means.

7. In combination, a treating unit, upper and lower drive shafts rotatably mounted therein, a pair of sprockets attached to each shaft, a pair of endless conveyor chains driven by said sprocket and adapted to carry skeins, the arrangement being such as to move the said chains in a zig-zag path through the unit, and means mounted on an upper shaft adapted to reverse the position of the skeins as they pass thereover.

8. In combination a treating unit, upper and lower drive shafts rotatably mounted therein, a pair of sprockets attached to each shaft, a pair of endless conveyor chains driven by said sprock-

et and adapted to carry skeins, the arrangement being such as to move the said chains in a zig-zag path through the unit, and means mounted on an upper shaft adapted to reverse the position of the skeins as they pass thereon, said means comprising a pair of parallel boards mounted tangentially to the shaft.

9. In a treating unit, a pair of endless conveyor chains, rods adapted to carry cakes secured thereto at spaced intervals, and means to compress the cakes to skein form comprising a first pair of rods and a second pair of rods located thereabove between which the said conveyor

chains are adapted to pass, the first pair being spaced further apart than said second pair.

10. In combination a pair of conveyor chains, shafts having pairs of sprockets secured thereto, over which the conveyor chains pass, the arrangement of the shafts being such as to move the chains in a zig-zag path, spaced receiving means mounted on said conveyor chains, carrier rods adapted to have skeins hanging therefrom positioned in said receiving means, and means located on certain of said shafts to reverse the position of the skeins on said carrier rods.
